CLAIM

The ornamental design for a swivel night light, as shown and described.

DESCRIPTION

FIG. 1 is a top, front, right side perspective view of a swivel night light showing my design in a first swivel position;
FIG. 2 is a top, front, right side perspective view of the swivel night light in a second swivel position;

FIG. 3 is a top, front, left side perspective view of the swivel night light in a third swivel position;

FIG. 4 is a front elevational view of the swivel night light in its first position;

FIG. 5 is a top plan view thereof;

FIG. 6 is a left side elevational view thereof;

FIG. 7 is a right side elevational view thereof;

FIG. 8 is a rear elevational view thereof; and,

FIG. 9 is a bottom plan view thereof.
